DESIGN FOR A DOORFRAME

Dwight J. Baum, New York, N. Y., assignor to
Curtis Companies Incorporated, Clinton, Iowa,
a corporation of Iowa

Application October 18, 1937, Serial No. 72,262

Term of patent 14 years

To all whom it may concern:

Be it known that I, Dwight J. Baum, a citizen of the United States and a resident of New York, in the county of Bronx and State of New York, have invented a new, original, and ornamental Design for a Door Frame, of which the following is a specification, reference being had to the accompanying drawing, forming part thereof.

Figure 1 is a perspective view of a door frame showing my new design.

Figure 2 is an enlarged vertical sectional view taken on the line 2—2 of Figure 1.

Figure 3 is an enlarged horizontal sectional view taken on the line 3—3 of Figure 1; and

Figure 4 is a still more greatly enlarged sectional view of the detail at A in Figure 2.

I claim:

The ornamental design for a door frame substantially as shown and described.

DWIGHT J. BAUM.
